UNITED STATES PATENT OFFICE.

WILLIAM W. LASKER, OF BROOKLYN, NEW YORK, ASSIGNOR TO POWERS ACCOUNTING MACHINE CORPORATION, OF NEW YORK, N. Y., A CORPORATION OF DELAWARE.

CARRIAGE RETURN FOR PUNCHING MACHINES.

Application filed October 22, 1925. Serial No. 64,174.

The present invention relates to punching mechanism for perforating cards in a predetermined manner, and relates more particularly to a control for the automatic return of the carriage by which the punch set-up is made. In machines of the character to which this invention relates there is a traveling carriage equipped with a single row of setting pins corresponding in number and 10 alinement to one row of the card to be punched and the construction is such that the carriage moves step by step across the card in response to the manual operation of keys by which the pins are selected. When 15 all of the pins are set to produce the predetermined arrangement of punches to perforate the particular card, a key is operated so that, with the card in register, means will function to cause the card to be perforated 20 by the punch set-up, and thereafter the punch set-up must be restored, the carriage returned to its initial position, and the set-up pins restored ready for a new set-up to 25 accord with statistics or data to be reproduced in the form of perforations upon another card.

The present invention is concerned more particularly with the return control of the carriage and adjuncts operated thereby.

Some of the objects of the present invention are to provide an improved automatic carriage return mechanism for card punching or perforating machines; to provide means for automatically returning a punching machine set-up carriage to any one of a predetermined initial punch set-up positions; to provide a control means, adapted to be set universally, and automatically operative to arrest the return of the carriage 30 which carries the set-up selecting devices; to provide means for automatically restoring the punch setting members by the operation of the carriage return elements; to provide means to eliminate shock and prevent breakage of the carriage return draw band tape; to provide a friction control device for returning the carriage to starting position; to provide means for automatically releasing 35 the carriage return means from the power transmitting means in case of excessive tension upon the return means; and to provide other improvements as will hereinafter appear.

In the accompanying drawings, Fig. 1 represents a side elevation of a punching machine embodying one form of the present invention; Fig. 2 represents a plan of the same; Fig. 3 represents a detail in sectional end elevation of the machine and its associated parts; Fig. 4 represents an end elevation of the machine; Fig. 5 represents a detail in section on line 5-5 of Fig. 1; Fig. 6 is a diagrammatic representation of the return control circuit showing a portion of the operating keyboard; and Fig. 7 is a detail showing the clutch latching mechanism.

Referring to the drawings, one form of carriage return mechanism embodying the present invention is shown as applied to a card punching machine of the type in which a carriage 10 carrying a row of vertically movable selecting pins 11 is arranged to travel across a cage or open frame 12 containing a plurality of set-up bars 13 which are respectively in vertical alinement with abutment pins 14 and these latter are respectively in vertical alinement with a plurality of punches 15. The set-up bars 13 are each suitably notched to form latches 16 for engagement with transversely arranged latch bars 17 which are automatically shifted, against the tension imposed by springs 18, by cam lugs 20 on the respective bars 17, to thus lock any set-up bar 13 which has been moved to set position. In set position of any of the bars 13 the alined abutment pins 14 are projected against the tension of springs 21 into close proximity to the head or heads of the punches 15 which are to perform the selected punching operation. The punches 15 are supported for vertical sliding movement in a guide plate 22 and have their lower ends respectively projecting into the perforations of an upper registration plate 23 which forms with a lower perforated registration plate 24 a passage 25 to receive the card. The plates 23 and 24 are part of a movable die 26 which is reciprocated by a suitable mechanism in timed relation to the cycle of operations. When a set-up has been made and a card is in the passage 25, the upward movement of the die 26 brings the card into contact with the lower ends of the punches 15 and those which are free to move are pushed upward by the movement of the die 26, while those

which are held by the set abutment pins 14 cannot move and therefore punch holes in the card at the desired locations.

In the punching machine here shown by 5 way of example, the selecting pins 11 are respectively arranged to be manually set by means of flexible wires or other connectors 27 which have connection with the respective keys 28 of the key-board of the machine. Thus any pin 11 which has been set is rigidly held against movement in the carriage frame and as the latter reciprocates the set pin will abut and set the selected set-bar 13. While the operating keys 28 10 correspond in number to the selecting pins 11, other keys are provided for other control purposes, such as a key 29 for causing the operation of the carriage return mechanism, a skip key 30 for line skipping, and 15 20 for any other control.

For causing the carriage 10 to travel across the field of set-up bars 13 to make a set-up, it is connected by a tape 31 to a spring winding drum 32 which is tensioned 25 to give the required travel to the carriage, while an escapement pawl 33 and ratchet 34 operating in conjunction with a rack 35 provides the desired step-by-step movement.

For returning the carriage 10 to a starting position, either aligned with the first row of set-bars 11 or any other selected row, a carriage return block 36 is mounted upon a track 37 for sliding movement parallel to the direction of movement of the carriage, and has a hook lug 38 projecting into the path of a pin 40 fixed to the carriage 10. The block 36 is also provided with a lift cam 41, the inclined face 42 of which is arranged to engage a roller 43 journalled on 30 an arm 44 of the carriage return lever 45, and by lifting it transmits motion to the lever 45 and through it to the link controlled arm 46 whereby the restoring roller 47 presses the cam triggers 47' to unlatch the bars 17 and restore the set bars 13 to normal position. One end of the carriage return block 36 is connected by a tape 48, or other suitable means, to a carriage return block tension drum 49, which being under 45 winding tension at all times operates to automatically return the block 36 as soon as it is released from a greater force acting to pull the block in the opposite direction against the tension of the drum 49. The 50 drum end of the tape 48 is connected to a strip bowed spring 48' joined to the drum 49 and serving as a shock absorbing device or compensator for any excess strain in the tape 48.

By this safety means abnormal pull upon the tape 48 is transmitted to the spring 48', and, due to its bowed form, automatically relieves the tape tension and prevents breaking of the tape. The opposite end of the block 36 is connected by a tape 50 leading to

and winding upon a friction driven drum 51. This drum 51 is mounted upon a bushing 52 which is fastened to a driven shaft 53, though any means for so securing the bushing 52 can be employed. Between the head of the bushing 52 and an adjusting nut 54 upon its end are two friction washers 55 receiving between them the disc body 56 of the drum 51, and the normal friction pressure created by the nut 54 causes the motion of the shaft 53 to be transmitted to the drum 51 to wind the tape 50. This friction is sufficient for all operating conditions of the punch carriage movements but in case the carriage should stick or for any other cause an abnormal strain be thrown upon the tape 50 then the drive friction will be overcome and the drum 51 can turn relative to the shaft 53, thereby preventing breakage of parts. 85

For transmitting motion to the shaft 53, bevel gears 57 and 58 are meshed and mounted to be driven by a shaft 60 which carries a movable clutch 61 arranged for clutching engagement with a clutch disc 62 having sprocket teeth 63 to be driven by a chain 64 which receives its motion from the main shaft of the machine. The movable clutch 61 is provided with suitable clutch pins 67, thrust bearings 68, adjusting collars 70, and a spring 71, the tension of which is adjusted by nuts 72. A ring 73 is interposed between the thrust bearings 68 and has trunnion connection with a clutch shift fork 74 which is mounted on a rock shaft in bearing brackets 75 for operation by an arm 74' controlled by a link 76. The opposite end of the link 76 is connected to a reset arm 77 pivoted at 78 to the main frame and having a lug 80 projecting into the path of movement of a carriage return bar 81. The link 76 is arranged to be held so that the clutch 61 is normally held out of clutching position by a pin 82 fixed to the link 76 and engaged by a latch 83 on an arm 84. This arm 84 is pivoted to the frame and is returned and held in latched position by a spring 85 stretched between the arm 84 and a fixed point. The end of the arm 84 opposite to the latch 83 is connected to the core 86 of a solenoid 87 which is included in an open electrical circuit, the closing of which takes place by the operation of the return key 29. 100

The carriage return bar 81 is mounted for limited sliding movement on studs 88 which pass through slots 89 formed in the bar 81, and the length of the slots 89 is such that the endwise movement of the bar 81 is sufficient to rock the reset arm 77 to release the clutch. 110

For transmitting movement to the bar 81 and also bringing the carriage 10 to rest properly aligned with the first row of set-bars 13, or any other selected row, an index stop 90 is provided and arranged for 120 130

sliding movement on the bar 81 but with provision for anchoring it to the bar 81 in any selected position. As here shown the lower edge of the bar 81 is provided with a plurality of notches 91 arranged to receive one or more tooth-like projections 92 on a keeper 93 which is pivoted to the index stop 90 and held tensioned toward the notches 91 by a spring 94 stretched between a pin 95 on the keeper 93 and a pin 96 on the index stop 90. A lock lever 97 is connected to the keeper 93 and slides relative to the stop 90 by the provision of a slot 98 and a stud 100, the last being fixed to the stop 90 and riding in the slot 98 to thereby guide the lever 97. Thus normally the index stop 90 is locked to the bar 81 by the spring 94 holding the projections 92 seated in the notches 91, but by pressing the lever 97 down, the keeper 93 is released from interlocked relation and may be moved longitudinally relative to the bar 91 to assume any new selected position.

For locating the index stop 90 so that the carriage 10 takes a position in register with any selected row of set-up bars 13, the bar 81 is numbered at intervals throughout its length corresponding to the number of rows or columns of set-up bars 13 in the field and proper setting of the index stop 90 is obtained by providing a sight opening 101 so located as to register with the numbers on the bar 81 and bring one number at a time opposite the opening 101. When the index stop 90 is set so that the carriage 10 takes an initial position in alinement with the first column of set-up bars 13, which is the position shown in Fig. 1, the index stop 90 abuts a laterally projecting pin 102 fixed to the bar 81, and by which movement is transmitted from the stop 90 to the bar 81 to cause operation of the reset arm 77. In other positions, the index stop 90, being locked to the bar 81, serves to give the desired end movement to actuate the reset arm 77.

In the operation of the punch, the index stop 90 is moved on the bar 81 so that the stop position is registered with the column of set-up bars 13 which has been selected as the starting point or initial setting of the carriage 10, and this setting of the stop is correctly made when the sight opening 101 shows the number corresponding to the selected column. Where the entire field of the card is to be traversed by the carriage 10, the index stop 90 will be set abutting the pin 102 and the opening 101 will show numeral 1. The operation of the keys 28 causes the carriage 10 to move row by row across the set-up bars 13 until the complete set-up has been made, and then the carriage return key 29 is depressed to close the circuit including the solenoid 87. The energization of the solenoid 87 shifts the core 86 to release the latch link 76 and thereby free the

movable clutch 61 to the action of the spring 71, so that motion is transmitted to the winding drum 51 through the friction clamping washers 55. The tape 50 winding on the drum 51 feeds the block 36 towards the carriage 10 and its lift cam 41 meets the roller 43 and raises it to the position necessary to throw the restoring roller 47 into operative relation with respect to the latches 17, and at the same time rocking the lever 45 to restore the carriage set-up. When the parts have been brought to such position, the return lug 38 on the block 36 picks up the pin 40 and causes the carriage 10 to return under the action of the block 36. The return movement of the carriage 10 continues until the collar 103 contacts with the index stop 90 which then follows the movement of the carriage and causes the bar 81 to also move through its limited travel to shift the reset lever 77. The movement of the reset lever 77 releases the clutch 61 and restores the latch link 76 to locking position. When this occurs the winding drum 51 is released to the tension of the block return tape 48 and the block 36 thereupon returns to its former position ready for its next carriage return movement.

By the provision of the friction connection between the winding drum and its driving mechanism any failure of the carriage 10 to move on its return will be taken up automatically, thus saving breakage of the tape or other parts and relieving the machine of the abnormal strain. Furthermore, the looped spring 48' attached to the tape 48 for returning the block 36 acts to relieve strain and shock upon the tape and its winding drum.

From the foregoing it will be apparent that a complete unitary carriage return mechanism has been provided wherein the initial position of the carriage can be changed at will to correspond to any one of many punching operations. Where, for example, the card is to be punched only in certain of the last fields of a card, starting, say, with column twenty of the card, the index stop 90 is released from the bar 81 and moved until the numeral 20 on the indicating strip shows at the sight opening 101. The locking lever 97 is then released to lock the stop 90 in that position and in consequence the carriage 10 returns only to that position of the stop and contacting therewith automatically releases the carriage from the return mechanism. The result of this construction is a flexibility of control and an increase in the speed of punching cards which only require data perforations in less than the whole number of columns.

While only a single form is shown in which this invention may be embodied, it is to be understood that the invention is not limited to any specific construction, but

might be applied to various forms without departing from the spirit of the invention or the scope of the appended claims.

Having thus described my invention, I

5 claim:

1. In a punching machine, the combination of a punch set-up carriage arranged to travel across the machine to make a punch set-up, means for automatically returning 10 said carriage, and means for varying the starting position of said carriage whereby the punch set-up can begin to operate at any selected column of a field of punches.

15 2. In a punching machine, the combination of a punch set-up carriage arranged to travel across the machine to make a punch set-up, means for automatically returning said carriage, and adjustable stop means in the return path of said carriage for stopping 20 said carriage in a predetermined position.

25 3. In a punching machine, the combination of a punch set-up carriage arranged to travel across the machine to make a punch set-up, means for automatically returning said carriage, adjustable stop means in the return path of said carriage for stopping said carriage in a predetermined position, and means for indicating the position of said stop means with respect to a column of 30 punches.

35 4. In a punching machine, the combination of a punch set-up carriage arranged to travel across the machine to make a punch set-up, means for automatically returning said carriage to a starting position, stop means arranged to be fixed in any one of a plurality of positions to thereby vary said starting position, and means controlled by said stop means for bringing said carriage 40 to rest in the selected starting position.

45 5. In a punching machine, the combination of a punch set-up carriage arranged to travel across the machine to make a punch set-up, means for automatically returning said carriage to a starting position, stop means arranged to be fixed in any one of a plurality of positions to thereby vary said starting position, and means controlled by said stop means for releasing said carriage 50 from said returning means, whereby said carriage stops in the selected starting position.

55 6. In a punching machine, the combination of a punch set-up carriage arranged to travel across the machine to make a punch set-up, means for automatically returning said carriage to a starting position, means including a movable bar for releasing said carriage from said return means, and a stop 60 adjustably mounted on said bar in the return path of a carriage part for operating said releasing means when said carriage reaches a predetermined starting position.

65 7. In a punching machine, the combination of a punch set-up carriage arranged to

travel across the machine to make a punch set-up, means for automatically returning said carriage to a starting position, means including a movable bar for releasing said carriage from said return means, a stop adjustably mounted on said bar in the return path of a carriage part for operating said releasing means when said carriage reaches a predetermined starting position, indicating characters on said bar corresponding to 70 punch columns, and means on said stop to designate the position of said stop with respect to each indicating character.

75 8. In a punching machine, the combination of a punch set-up carriage arranged to travel across the machine to make a punch set-up, means for automatically returning said carriage to a starting position, means including a movable bar for releasing said carriage from said return means, a stop adjustably mounted on said bar in the return path of a carriage part for operating said releasing means and provided with a sight opening, and indicating characters on said 80 bar in alignment with said sight opening and corresponding to punch columns.

85 9. In a punching machine, a carriage arranged to travel across the machine to make a punch set-up, power driven means for returning said carriage to a starting position, and a friction connection between said carriage and said driven means whereby said carriage is automatically released from said driven means under abnormal conditions.

90 10. In a punching machine, a carriage arranged to travel across the machine to make a punch set-up, power driven means for returning said carriage to a starting position, a tape connecting said carriage to said driven means, and means for automatically releasing said carriage from said driven means when an abnormal tension is applied to said tape.

95 11. In a punching machine, a carriage arranged to travel across the machine to make a punch set-up, power driven means for returning said carriage to a starting position, a tape connecting said carriage to said driven means, a winding drum for said tape, and friction means for connecting said drum to said driven means whereby said carriage is automatically released from said driven means when an abnormal tension is applied to said tape.

100 12. In a punching machine, a carriage arranged to travel across the machine, means for returning said carriage to its starting position, a device normally maintaining said returning means inoperative, means including a solenoid for releasing said device to cause said returning means to function, and adjustable stop means for said carriage for resetting said device to stop said returning means whereby the starting position of said carriage can be varied at will.

13. In a punching machine, a carriage, a carriage-return element, means including a winding drum and a tape for causing said carriage-return element to travel transversely of the machine in one direction, and strain relieving means between said tape and said winding drum. 10
14. In a punching machine, a carriage, a carriage-return element, means including a winding drum and a tape for causing said carriage-return element to travel transversely of the machine in one direction, and a loop spring interposed between said tape and said winding drum. 15

Signed at Philadelphia, county of Philadelphia, State of Pennsylvania, this 15th day of October, 1925.

WILLIAM W. LASKER.
